CURB INLET CASTING

De Witt S. Crocker, Springfield Gardens, N. Y.

Application March 29, 1950, Serial No. 152,589

8 Claims. (Cl. 182—6)

1

This invention relates to curb inlets for catch basins of the type shown in my prior Patent No. 2,473,279, issued June 14, 1949.

The general object of the curb inlet of the said patent and of this application is to provide a curb inlet casting which will integrally unite the side walls of the catch basin and the sidewalk slab thereof so that the inlet casting will move therewith as the concrete structure expands and contracts with temperature changes and will remain fixedly bonded thereto, and so that the curb inlet casting itself will not move relatively to the wall and roof structure of the catch basin under said temperature changes.

In the aforesaid patent, these ends are achieved by providing the end walls of the inlet casting with a pair of protuberances extending outwardly and generally longitudinally of the casting and which present a vertical dimension substantially centered at the juncture of the side walls of the catch basin and the sidewalk slab thereof, with the lower portions of the protuberances embedded in the side walls and with the upper portions of the protuberances embedded in said sidewalk slab.

One of the objects of the present invention is to provide a curb inlet casting as described above, in which the said protuberances have modified and improved or alternative constructions.

Another object is to provide a curb inlet casting as described, implemented with means of additionally tying or securing the casting to adjacent structures such as the catch basin, the sidewalk slab, or the gutter grating.

For the attainment of the foregoing and such other objects of invention as may appear or be pointed out herein, I have shown several forms of my invention in the accompanying drawings, wherein:

Fig. 1 is a perspective view of the improved curb inlet;

Fig. 2 is an elevational section through the unpaved catch basin and curb inlet casting;

Fig. 3 is a top view, partially in section on the line 3—3 of Fig. 2;

Fig. 4 is a fragmental elevational sectional view (similar to Fig. 2) but showing a modified form; and

Fig. 5 is a fragmental elevational sectional view, like Fig. 4, showing a modification thereof.

The improved curb inlet casting, generally designated 10, comprises a base plate 11 and an upper bar 12, between which may be provided a plurality of intermediate partitions 13, integrally united at their lower portions with base plate 11

and at their upper portions with longitudinal bar 12. Intermediate partitions 13, of which five are shown in Fig. 1, for exemplification, provide a plurality of wide openings 15 in front of the casting.

The partitions 13, as best seen in Figs. 1 and 2, are shown as of irregular triangular shape with the base thereof at the front of the casting and with their apices 17 rearwardly disposed. These partitions are shown in the drawings as equally spaced from each other and from the end walls, 14, 14, of the casting.

Projecting longitudinally outwardly of the end walls 14, 14 are a vertically disposed flange or protuberance 20 and a horizontally disposed flange or protuberance 21. The vertical protuberance 20 is shown as located substantially at the medial vertical plane through end wall 14, Fig. 1 (see also Fig. 2) and the horizontal protuberance 21 is shown as located substantially at the medial horizontal plane therethrough. Horizontal protuberance 21 is shown as normal to the vertical one 20 and as extending rearwardly therefrom and as substantially coplanar to the medial horizontal plane through the apex 17 of the end wall.

The protuberances 20, 21 are so disposed and dimensioned that the lower portions thereof are embedded in the side walls 9, 9 of the catch basin, see Figs. 4-5, and the upper portions thereof are embedded in the sidewalk slab 6.

The base 11 of the improved curb inlet casting is disposed at the top surface of front wall 2 of the catch basin, this being substantially level with the subgrade 3, which is stepped down from the level of sidewalk slab 6. The aforesaid front bar 12 of the improved curb casting constitutes the curb at the sidewalk stepdown. The aforesaid sub-grade 3 is further depressed below the roadway level 5 to form a gutter, which is covered by the gutter grating 4.

The front of the catch-basin (where the curb inlet casting is placed) is completed by a front wall 2 of concrete, which is integrally united, see Fig. 3, with the side walls 9, 9. As best shown in Fig. 2, the front wall 2 does not unite with the sidewalk slab 6 but presents its top surface spaced a short distance below the sidewalk slab. After the side walls 9, 9 of the catch basin and its front wall 2 are poured, the inlet casting 10 is placed in position along the front of the basin, with the base plate 11 of the casting resting upon the aforesaid top surface of front wall 2. Thereafter, the sidewalk slab 6 is poured, to unite the casting in place.

As a result of the embedding of the protuberances **20, 21** in the side walls and sidewalk slab of the catch basin as described above, these and the front wall of the catch basin are integrally united together, so that all parts of the catch basin expand and contract together. Additionally, the curb inlet casting is bonded thereto and is prevented from moving relative to the catch basin.

The horizontal protuberance 21 may be provided with an aperture 23, and the base plate 11 may be provided with an aperture 19, positioned preferably near the end walls 14, 14. The apertures 23, 19 serve to increase the effectiveness of the bonding of the curb inlet casting to the catch basin and the sidewalk slab. They may also serve to additionally bond the curb inlet casting to the adjacent structures in the manner shown in Figs. 4 and 5. The curb inlet casting may be tied in with the reinforcing rods 6* of the sidewalk slab as shown in Fig. 4, as by means of connecting rods 24 shown as formed at its upper end into a hook 25 which is slipped about one of the reinforcing rods. The rod 24 is passed through aperture 23 and is shown as formed at its lower end with a hook 26.

The casting may be tied to the reinforcing rods 2^x of front wall 2 of the catch basin, by means of a connecting rod 21, which passes through aperture 19 of base plate 11 of the improved casting, the end being formed in hook 22. The lower end of connecting rod 21 is formed into a hook 29, which passes around one of the reinforcing rods 2^x.

The tying-in with the reinforcing rods 2^x of the front wall 2 of the catch basin may be achieved by a connecting rod 31, Fig. 5, the upper end of which passes through the aperture 23 in the horizontal protuberance 21, this end being formed into hook 34. The lower end of the rod is formed into a hook 39 which passes around one of the reinforcing rods 2^x of the front wall of the catch basin.

The openings 19 may serve also for tying in the street inlet or gutter grating 4 to the curb inlet casting by means such as plate 38. This plate is shown as having one leg bolted at 31 to the curb casting through opening 19 and the other leg bolted at 32 to the gutter grating by upstanding flange 33.

The construction of the illustrated embodiment has been set forth in full detail because it is that practical embodiment which it is believed will attain most effectively the objects of the invention. It will be understood, however, that such details are not to be considered as essential unless expressly so stated in the claims.

I claim:

1. In a road drainage catch basin, in combination, a pair of concrete side walls defining the lateral limits of the catch basin, a concrete front wall presenting its upper edge substantially level with the road subgrade, a concrete sidewalk slab integral with said side walls to cover the catch basin, and a curb inlet casting having a base which is disposed at the upper edge of said front wall of the catch basin, and a pair of end walls, each end wall having a pair of angularly related protuberances extending outwardly therefrom, one of said pair of protuberances being generally vertically extended, and another being generally horizontally extended, said protuberances having their mid-portions in the separation plane between the sidewalk walls and the basin side walls, whereby the lower portions of the pro- 70 75

tuberances are disposed in the side walls of the catch basin after it is poured and the upper portions thereof are disposed in the said wall slab when it is poured.

5 2. The combination according to claim 1
wherein said sidewalk slab is provided with re-
inforcing rods, and wherein one of said pro-
tuberances is apertured, and a short connecting
rod passes through said aperture, the upper end
10 thereof being hooked over one of said reinforcing
rods, and the lower end of the connecting rod
being hooked in underlying relation to said pro-
tuberance.

3. The combination according to claim 1
15 wherein said front wall of the catch basin is provided with reinforcing rods and wherein said base of the curb inlet casting is apertured near the end walls, and a connecting rod passes through said aperture, the lower end thereof being hooked over one of said reinforcing rods, and the upper end of the connecting rod being hooked in overlying relation to said base of the casting.

4. In a road drainage catch basin, in combination, a pair of concrete side walls defining the lateral limits of the catch basin, a concrete front wall presenting its upper edge substantially level with the road sub-grade, a concrete sidewalk slab on the said side walls to cover the catch basin, and a curb inlet casting having a base which is disposed at the upper edge of said front wall of the catch basin, and a pair of end walls, each end wall having a pair of protuberances extending outwardly therefrom, one of said protuberances being generally vertically extended and the other being generally horizontally extended, said protuberances having their mid-portions in the separation plane between the sidewalk slab and the basin side walls, the portions of the protuberances above said plane being disposed within the sidewalk slab and the portions therebelow being disposed in said side walls, said end walls being triangularly shaped and presenting their apices rearwardly in said separation plane.

5. In a road drainage catch basin, in combination, a pair of concrete side walls defining the lateral limits of the catch basin, a concrete front wall presenting its upper edge substantially level with the road sub-grade, a concrete sidewalk slab integral with said side walls to cover the catch basin, and a curb inlet casting having a base which is disposed at the upper edge of said front wall of the catch basin, a plurality of partitions and a pair of end walls, each end wall having a pair of protuberances extending outwardly therefrom, one of said protuberances being generally vertically extended and the other being generally horizontally extended, said end walls and partitions being triangularly shaped and presenting their apices rearwardly in the separating plane between the sidewalk slab and the basin side walls to define upper portions which are disposed within the sidewalk slab and lower portions which are disposed in said side walls.

6. The combination according to claim 5 where-
in said catch basin has a grating disposed in the
road in front of the curb inlet casting, the base
of said casting having an aperture near each end,
said grating being detachably connected to the
curb inlet casting by a member which is bolted
through said aperture.

7. A curb inlet casting for a road drainage catch basin which is comprised of a pair of concrete side walls defining the lateral limits of the

catch basin, a concrete front wall presenting its upper edge substantially level with the road sub-grade, and a concrete sidewalk slab to cover the catch basin; said curb inlet casting having a base to be disposed at the upper edge of said front wall of the catch basin, and a pair of end walls, each end wall having a pair of protuberances extending outwardly therefrom, one of said protuberances being generally vertically extended and the other being generally horizontally extended, the protuberances being of a vertical dimension so that the lower portions thereof will be disposed in the side walls of the catch basin when they are poured and the upper portions thereof will be disposed within the sidewalk slab when it is poured.

8. A curb inlet casting for a road drainage catch basin which is comprised of a pair of concrete side walls defining the lateral limits of the catch basin, a concrete front wall presenting its upper edge substantially level with the road sub-grade, and a concrete sidewalk slab to cover the

catch basin; said curb inlet casting having a base to be disposed at the upper edge of said front wall of the catch basin, a plurality of partitions and a pair of end walls, each end wall having a pair of protuberances extending outwardly therefrom, one of said protuberances being generally vertically extended and the other being generally horizontally extended, the end walls and partitions being triangularly shaped and presenting their apices rearwardly in the separating plane between the sidewalk slab and the basin side walls to define upper portions which are disposed within the sidewalk slab.
